UNITED STATES PATENT OFFICE.

HOWARD L. MOULE, OF RICHLFIELD, UTAH.

DESIGN FOR A BOX-FASTENER.

SPECIFICATION forming part of Design No. 32,580, dated April 24, 1900.

Application filed March 20, 1900. Serial No. 9,459. Term of patent 14 years.

To all whom it may concern:

Be it known that I, HOWARD L. MOULE, a citizen of the United States, and a resident of Richfield, in the county of Sevier and State 5 of Utah, have invented and produced a new and original Design for a Box-Fastener, of which the following is a full, clear, and exact description.

Reference is to be had to the accompanying 10 drawings, forming a part of this specification, in which similar characters of reference indicate corresponding parts in both figures.

Figure 1 is a perspective view of a box-fastener exhibiting my design, and Fig. 2 is a 15 face view thereof.

The leading feature of my design consists of a box-fastener made of keystone shape in outline—that is, with a horizontal top edge A and downwardly-converging side edges A', a

slot A² extending from the central portion of 20 the fastener to the bottom. The lower end of said slot is flaring, the fastener having at this point upwardly-converging edge portions A³, while at the upper end of the slot there is a circular enlargement A⁴. The upper 25 portion of the fastener has through-apertures A⁵, the edges of which are beveled, as are also those forming the outline of the fastener.

Having thus described my invention, I claim as new and desire to secure by Letters 30 Patent—

The design for a box-fastener, as herein shown and described.

HOWARD L. MOULE.
